(57) **CLAIM**

The ornamental design for a hand-held device, as shown and described.

DESCRIPTION

The invention was made with government support under government contract DAAH01-01-C-R003 awarded by DARPA via Army Aviation & Missile Command, Redstone Arsenal. The United States Government has certain rights in the invention.

FIG. 1 is a front perspective view of a hand-held device embodying our design;

FIG. 2 is a rear elevational view thereof;

FIG. 3 is a right side elevational view thereof, the left side elevational view being a mirror image thereof;

FIG. 4 is a rear perspective view thereof;

FIG. 5 is a front elevational view thereof;

FIG. 6 is a top plan view thereof; and,

FIG. 7 is a bottom plan view thereof.
